MOLDED BOX FOR ELECTRIC SWITCHES

James C. Powell, Elkhart, Ind., assignor to
All-Steel Equipment Inc.

Filed Nov. 15, 1971, Ser. No. 199,091

Term of patent 14 years

Int. Cl. D13—03

U.S. Cl. D26—5 B

Fig. 1.

Fig. 2.

Fig. 3.

Fig. 4.

Fig. 5.

Fig. 6.

FIG. 1 is a frontal perspective view of a molded box for electric switches;

FIG. 2 is a rear perspective view of the box shown in FIG. 1;

FIG. 3 is a top plan view of the box;

FIG. 4 is a side elevational view of the box taken from the right hand side of FIG. 3;

FIG. 5 is a bottom plan view of the box;

FIG. 6 is a side elevational view of the box taken from the left hand side of FIG. 3;

FIG. 7 is an end elevational view of the box taken from the bottom side of FIG. 3;

FIG. 8 is a sectional view of the box taken along line 8-8 of FIG. 7;

FIG. 9 is a sectional view of the box taken along line 9-9 of FIG. 7;

FIG. 10 is a fragmental cross-sectional view of the box taken along line 10-10 of FIG. 3; and

FIG. 11 is a fragmental cross-sectional view of the box taken along line 11-11 of FIG. 5.

I claim:

The ornamental design for a molded box for electric switches, substantially as shown.
